(57) **CLAIM**

The ornamental design for a bracing for a hook, as shown and described.

DESCRIPTION

FIG. 1 is a front perspective view of a bracing for a hook, showing my new design;

FIG. 2 is a back perspective view thereof;

FIG. 3 is a right side elevation view thereof;

FIG. 4 is a left side elevation view thereof;

FIG. 5 is a front elevation view thereof;

FIG. 6 is a back elevation view thereof;

FIG. 7 is a top plan view thereof;

FIG. 8 is a bottom plan view of thereof; and,

FIG. 9 is a perspective view showing the bracing for a hook of FIGS. 1 through 8 with mechanical fasteners aligned for engagement with the fastener holes of the bracing for a hook, that can, for example, be used for mounting the hook to a support surface.

The details shown in broken lines are for illustrative purposes only and form no part of the claimed design.
